Specification of Letters Patent. Patented Jan. 25, 1921.

Application filed May 17, 1915. Serial No. 28,699.

To all whom it may concern:

Be it known that we, CHARLES L. KRUM and HOWARD L. KRUM, citizens of the United States, and residents of Chicago, county of Cook, and State of Illinois, have invented certain new and useful Improvements in Selective or Printing Telegraphs, of which the following is a full, clear, and exact description.

10 The invention relates to selective or printing telegraphs in which the characters or signals are represented by combinations of impulses, and in which the transmission of the signals or combinations of impulses is controlled by the formation of a tape.

The present invention seeks to provide means whereby the tape can be fed directly from the tape-forming or punching mechanism to the transmitter, and to provide improved means whereby any cessation of the operation of the tape-forming or punching mechanism will automatically throw the tape-feeding means of the transmitter out of operation and whereby the renewed operation of the tape-forming or punching mechanism will automatically throw the feeding means of the transmitter into operation. Further objects of the invention are to provide improved means for interrupting not only the tape-feeder of the transmitter, but also the transmission of the impulses, and to provide interrupting means which will act only between completed signals.

The invention also seeks to provide, in a synchronous telegraph, means controlled by the tape-forming or punching mechanism for throwing the tape-feeding and signal-transmitting means of the transmitter into and out of operation, but which will not interrupt the transmission of the correcting impulses by which the instruments at the sending and receiving stations are maintained in synchronism. A further object of the invention is to provide an improved station instrument having tape-controlled means for throwing the tape-feeder into and out of operation, and for interrupting the transmission of the signals.

With these and other objects in view, as will presently appear, the invention consists in the features of improvement hereinafter set forth, illustrated in the preferred form and arrangement in the accompanying drawings and more particularly pointed out in the appended claims.

In the drawings, Figure 1 is a view in elevation of one of the improved station instruments. Fig. 2 is an elevation of the right-hand end of the instrument shown in Fig. 1. Figs. 3 and 4 are detailed sections on the lines 3—3 and 4—4 respectively of Fig. 1. Fig. 5 is a detailed horizontal section on the line 5—5 of Fig. 2. Fig. 6 is a plan view of a station instrument of modified form. Fig. 7 is a diagrammatic view illustrating the arrangement of the tape-forming or punching mechanism and the transmitter at one station and the arrangement of the receiver at another station. Fig. 8 is a view of a short section of the tape.

Any suitable mechanism for forming or punching the tape may be employed, and can be actuated by a receiver mechanism under control of signals transmitted from a distant station, or, as usual, by a set of finger keys. A punch mechanism similar to that set forth in our Letters Patent of the United States No. 1,182,179, dated May 9, 1916, is diagrammatically illustrated in Fig. 7. In this punch mechanism, the tape A is fed through a passage or guide-way formed between a plate 10 and a die-block 11. The die-block 11 is provided with punches for embossing, or preferably perforating the tape, and, in the present instance, as set forth in the prior patent referred to, punches are arranged to form transverse rows of holes a in the tape (see Fig. 8), the perforations in the separate rows being varied so that each row respects a different character or signal. The tape-forming mechanism is also provided with a punch for forming a longitudinal row of small perforations 13, which are adapted to be engaged by pin-toothed feed wheels to advance or feed the tape.

A pivoted, spring-held punch actuator 14 is connected by a rod 15 to the armature b of a magnet B and the punches 12, which form the transverse rows of perforations a, are controlled by a set of selecting bars 16, which are connected to the actuator 14 to swing therewith, but are longitudinally shiftable, so that their ends can be shifted into and out of line with the punches 12. The selecting bars 16 are actuated by a set of bell cranks 17 and the latter in turn are operated by a series of upwardly projecting lugs upon a set of bails 19. Only one selecting punch and one bell crank 17 are shown,

it being understood that these parts are arranged in vertical series, as set forth in the above noted patent.

The bails 19 are variably controlled by a set of finger keys 20 (only two of which are shown) and which are provided with lugs 21 for variably actuating the bails. Each key, however, is arranged to operate the outermost bail, which operates an arm 22 arranged above the set of bell cranks 17 and which carries an insulated switch arm 23. Thus, whenever a key is actuated, one or more of the selecting bars 16 are shifted and a circuit is closed from a battery wire 24 to the switch arm 23, thence from the contact of this switch by a conductor 23' through the magnet B to the ground. The magnet is thus energized to shift the actuator 14 and operate the punches. The shift of the actuator also advances the tape through the punch mechanism intermittently or step-by-step. For this purpose, it is provided at its outer end with a spring-held pawl 25 which is arranged to engage the teeth of a ratchet 26, the ratchet being connected to a pin-toothed feed wheel 27, which is arranged to engage the perforations 13 of the tape. As the actuator is moved forwardly to punch the tape, the pawl 25 moves idly over the teeth of the ratchet 26, but on the backward movement of the actuator, the ratchet and feed wheel 27 are advanced one step. A pressure roll 28, provided with slots therein to receive the teeth of the pin wheel 27, is arranged to hold the tape in snug engagement with the feed wheel. Preferably, also, the tape passes around a guide plate 29, which is so located that the tape is engaged by a number of the teeth of the feed wheel. By such a tape-punching mechanism, or its equivalent, the tape is formed in accordance with the signals or characters to be transmitted.

In accordance with the present invention, the tape, as it is formed and intermittently advanced by the punch mechanism, is fed directly to the transmitter, which is provided with a tape feeder. This feeder in the preferred construction shown is in the form of a horizontal feed wheel 30 arranged at one end of the base plate 31 of the improved station instrument. The feed wheel is arranged behind an upright plate 32 on the base plate and the wheel projects through a slot in the plate 32, so that its teeth extend into a tape guide-way formed between the front face of the plate 32 and a narrow, thin plate 33, as most clearly shown in Fig. 5. The plate 33 is fastened to the front of the plate 32, but is spaced therefrom as shown. The teeth of the pin-toothed wheel 30 of course engage the perforations 13 of the tape and advance the same, so that the transverse rows of perforations coöperate with a vertical series of selecting switches C.

The switches C extend through a series of eccentrics 34 on an upright shaft 35, the latter being fixed at its lower end to a small base plate 36 which is insulated from the main base plate 31. The inner, pointed ends of the switches project into the tape guide-way between the plates 32 and 33. The outer portions of the switches C extend through the guiding comb bar 37 and their extreme outer ends are provided with contacts which coöperate with a series of insulated contact screws 38 that are carried by an upright plate 39. A series of springs 40 tend to hold the switches in engagement with the contact screws, but as the tape engages the inner, pointed ends of the switches, each switch will be held out of engagement with its contact screw unless it drops into one of the perforations of the tape. In this way, the switches C are variably actuated to select the combinations of impulses as the tape is advanced by the feed wheel 30. As the tape is advanced, it is deflected forwardly by a guide plate 41, which projects forwardly from the inner edge of the plate 32.

The feed wheel 30 is mounted upon the lower end of a shaft 42. In the construction shown, this shaft is journaled in a sleeve 43 which depends from a support or head 44. The latter is swiveled upon one end of a horizontal shaft 45. The support or head 44 is provided with a chamber or recess open at its upper portion and a worm 46 and a worm wheel 47 are arranged within this recess and are fixed respectively to the shafts 45 and 42 to form a driving connection between the shaft 45 and the feed wheel 30. The sleeve 43 is provided at its upper end with a rearwardly projecting finger-piece 48 and by means of this finger-piece, the support 44 and parts carried thereby can be swung through a short arc about the shaft 45, to thereby move the feed wheel 30 out of the path of the tape, so that the tape can be readily placed within the guide-way or removed therefrom. This oscillating movement of the support 44 and the parts carried thereby, is guided by a U-shaped guide bracket 49 (see Figs. 2 and 5) which projects rearwardly from the plate 32 and engages flattened faces on the lower end of the sleeve 43. A spring 50 extends between the bracket 49 and the finger 48 and holds the parts in the normal position shown in Fig. 2, with a lug 51 on the sleeve 43 engaging a stop screw 52 that is adjustably threaded through the upper end of the plate 32. An insulated arm 53 is connected to the head 44 and extends downwardly therefrom. Its lower end engages the forked outer end of a lever 54, which is mounted upon the upright shaft 35. The inner end of this lever carries a vertical pin 55 (see Fig. 5) and, when the support 44 is shifted to move the

feed wheel 30 out of the path of the tape, the pin 55 engages the switches C and swings them about the shaft 35 so that their inner ends are also shifted out of the path 5 of the tape. A similar arrangement of tape feeder and tape-controlled selecting switches is set forth and claimed in the prior application filed by us in the United States Patent Office March 7, 1914, Serial No. 10 823,100.

As set forth in said prior application, the tape feed wheel is preferably continuously driven during the transmission of messages to continuously advance the tape. In accordance with the present invention, means is provided for throwing the tape feeding mechanism into and out of operation. For this purpose, the shaft 45 is connected to a motor through the medium of a clutch, and 20 means, preferably a tape-actuated switch, controls the operation of the clutch and in turn is controlled by the operation of the tape-forming or punching mechanism. In the construction shown in Figs. 1 and 2, the 25 shaft 45 is journaled at its outer end in a cross-piece 56, which extends across a circular opening in the upper portion of a vertical bracket 57 that projects upwardly from the base plate 31. The opposite end of the 30 shaft, as shown in dotted lines in Fig. 1, extends within a bore formed within an aligned shaft 58. The latter is journaled at its outer end in the cross-bar 59 which extends across the circular opening at the upper portion of 35 a bracket 60 similar in construction to the bracket 57. The inner end of the shaft 58 is journaled in the upper end of a U-shaped bracket 61 (see Figs. 1 and 3). The left-hand end of the shaft 58 is provided with a 40 gear 62 which meshes with the teeth of a pinion 63 on the shaft of a small electric motor 64. In this way, the shaft 58 is continuously driven during the operation of the machine and suitable governor mechanism 45 (not shown) is provided for maintaining the speed of the motor and the shaft 58 uniform.

The shaft 58 and the drive shaft 45 of the tape feeder are connected by a clutch, which, 50 in the preferred construction shown, comprises a clutch disk 65 fixed to the end of the shaft 58, an arm 66 fixed to the adjacent end of the shaft 45 and a clutch dog 67 which is pivotally mounted on the arm 66 55 and which is pressed by a spring 68 into engagement with the clutch disk 65. In the preferred construction shown, the dog is provided with a tooth 69, which, when the clutch members are connected, engages a 60 single notch 70 formed in the periphery of the clutch disk 65.

Beneath the clutch members is arranged a solenoid magnet D. This magnet is mounted in a U-shaped frame 71 and the core d of 65 the magnet is connected to the lower end of

a lever 72. The lever is pivoted intermediate its ends to a lug 73' on the bracket 71, and its upper end is connected to a trip pin 73 which is adapted to engage the clutch dog 67 and disengage it from the clutch disk 65. 70 The trip pin 73 is mounted to slide through the upper portion of a U-shaped bracket 74 that is mounted on the bracket 71 and a spring 75, connected to the bracket 74 and to the trip device, is arranged to project the 75 latter into the path of movement of the clutch dog 67. But, when the magnet D is energized, the trip pin is withdrawn and is held in the position shown in Fig. 1, out of the path of movement of the clutch dog. 80

The circuit of the magnet D is controlled by a pair of insulated contacts 76 and 77 (see Fig. 5), the contact 77 being fixed in position on the base plate and the contact 76 being mounted upon the short arm 78 of a bell crank switch lever F. This bell crank is pivoted to the base plate at 79, and its longer arm 80 extends horizontally behind the plate 32. The arm 80 is provided with a curved end which projects forwardly in front of the 90 tape guide-way and is provided with an upwardly projecting pin 81 which engages the tape (see Fig. 7) as the latter passes between the respective feeders of the tape former and the transmitter. A spring 82 95 connected to the shorter arm of the bell crank normally holds the contacts 76 and 77 in engagement, so that the circuit of the magnet D is held closed and the trip device 100 73 out of the path of the clutch dog 67.

The tape-forming or punching mechanism is, of course, operated independently of the transmitter and if it is operated with sufficient frequency and speed to maintain slack in the tape between the former and the feed-wheel 30 of the transmitter, the switch contacts 76 and 77 will remain in engagement, but if the operation of the tape-former is arrested, the continued operation of the transmitter mechanism will place the tape 105 under tension and will thereby shift the arms 80 and 78 of the switch lever F, disengage the contact 76 from the contact 77 and open the circuit of the magnet D. The spring 75 will then project the trip pin 73, and, when the clutch dog strikes the trip pin, it will be disengaged from the clutch disk 65 and the operation of the tape-feeder of the transmitter will be arrested. As soon 110 as the operation of the tape former is resumed, the portion of the tape between it and the transmitter will become slack and spring 82 will reengage the contacts 76 and 77, energize magnet D and return the trip pin 73 to its normal position. The dog 67 115 will then reengage the clutch disk 65 and the tape feeder of the transmitter will again be thrown into operation. In this way, the tape feeder of the transmitter is automatically thrown into and out of operation by 120

125 65 the magnet is connected to the lower end of

trip devices which in turn are controlled by the operation of the tape former.

The shafts 58 and 45 are driven in the direction indicated by the arrow in Fig. 3, and preferably the pivoted clutch dog 67 is rearwardly inclined with reference to the direction of movement, as shown, so that it may be readily disengaged when it strikes the trip pin 73. To prevent the backward movement of the shaft 45 when the clutch dog is disengaged, a disk 83 is fixed to the shaft 45 adjacent the arm 66, and is provided with a recess at one point having a shoulder 84. When the clutch dog 67 is disengaged, a spring arm 85, which projects upwardly from the bracket 71, is arranged to engage the shoulder 84 and hold the shaft 45 and parts connected thereto against backward movement.

As the tape is advanced by the transmitter feed wheel 30, the transverse rows of openings *a* therein are successively brought opposite the inner pointed ends of the switches C. The body of the tape will hold the switches out of engagement with their co-operating contacts, but, when any switch drops into a perforation, it is quickly shifted by its spring into engagement with its contact. The switches thus serve to select the combinations of impulses, which are transmitted to the line by suitable switch mechanism operating in timed relation with the tape feed wheel 30. The transmitter switch mechanism preferably comprises a rotary or so-called "sun-flower" switch arm *e* which is arranged to move over a series of contacts 1, 2, 3, 4, 5 and 6 mounted upon a disk E (see Figs. 1, 5 and 7). The switch arm *e* is arranged to rotate in unison with the shafts 45 and 58. In an instrument designed for telegraph systems which do not require the transmission at regular intervals of synchronizing impulses, the switch arm *e* could be mounted on the shaft 45 so as to be thrown into and out of operation with the tape feeder. But the improved instrument is more particularly designed for telegraph systems in which synchronizing or correcting impulses are imparted at regular intervals to the line whether or not character signals are also transmitted and the transmitter switch arm *e* is mounted upon the shaft 58 with the co-operating annular disk E mounted upon the upper annular portion of the bracket 60 and surrounding the shaft. The disk E is provided with two additional contacts 7 and 8 (see Fig. 7) and the transmitter switch arm is continuously rotated during the operation of the machine, so that even if the feed of the tape be interrupted, correcting impulses will be transmitted over the line as the switch arm passes over the contacts 7 and 8.

The set of five selecting switches C serve to variably connect the contacts 1, 2, 3, 4 and

5 of the transmitter disk E to a source of current, to thereby select the combinations of impulses which represent the different characters or signals, and which are transmitted to the line as the switch arm *e* passes over these contacts. In the preferred form shown, the passage of the switch arm *e* over the contact 6 is arranged to transmit a re-storing impulse, and, as above stated, the passage of the switch arm over the contacts 7 and 8 transmits a correcting impulse. When the switch F is shifted by the tape, the magnet D is at once de-energized and trip pin 73 is projected. But the clutch members are not disengaged until the connected shafts 45 and 58 are moved far enough to bring the clutch dog 67 into engagement with the trip pin 73. The shafts 45 and 58 and the parts connected thereto rotate in the direction indicated by the arrows in Figs. 3 and 7 and the clutch dog 67 is definitely positioned relatively to the transmitter switch arm *e* so that it cannot come into engagement with the trip pin until the switch arm occupies a position between the contacts 6 and 1. Hence the trip devices are only operative at the end of the transmission of a completed character signal.

It should also be noted that in the preferred construction shown, which is adapted for a synchronous telegraph system in which correcting impulses are imparted to the line at regular intervals whether or not character signals are also transmitted, the notch 70 in the clutch disk 65 occupies a definite position relatively to the switch arm *e*, so that the clutch members can only be re-engaged when the transmitter switch arm *e* is in position to commence the transmission of a character signal. In the preferred construction shown, the clutch mechanism is so arranged that the members thereof are engaged and disengaged as the transmitter switch arm *e* passes over the contacts 7 and 8, which, as stated, serve to transmit the correcting impulses, and which are transmitted independently of the tape which selects the character signals. By reason of this construction, the clutch members connect the transmitter switch and the tape-feeder in definite relation and the trip mechanism is only operative between completed signals to arrest the feed of the tape.

The selecting switches C, as stated, serve to variably connect the contacts 1, 2, 3, 4 and 5 of the transmitter disk to a source of current and preferably a second set of five switches *g* (see Fig. 7) are interposed between the selecting switches C and the transmitter disk, the switches *g* being operated by a set of magnets G. The selecting switches C are all connected to one of the branches of the conductor 24, which leads from the local battery H, and the contacts of these switches are connected respectively

by a set of conductors 85 to the coils of the magnets G, the latter being also connected to the ground or by a suitable return conductor to the local battery H. The switches 5 g are connected respectively by a set of conductors 86 to the contacts 1, 2, 3, 4 and 5 of the transmitter disk.

The characters are preferably represented by permutations of five impulses of opposite polarity. For this reason, the switches g form pole changers, the contacts of which are connected by conductors 87 and 88 to the opposite sides of a divided battery H', the normally engaged or back contacts being 15 connected to the negative pole of a battery by the conductor 87 and the normally disengaged or front contacts to the positive pole thereof by the conductor 88. The conductor 88 leads directly from the positive pole of 20 the battery H', but, for purposes hereinafter described, a switch j is interposed in the conductor 87. The conductor 87 also extends to the contact 6 of the transmitter disk E, and the conductor 88 from the positive pole 25 of the battery is connected to the contact 8. The contact 7 of the transmitter disk is permanently connected to the negative pole of the battery by a conductor 89. As the transmitter switch e passes over the contacts 1, 30 2, 3, 4 and 5, it imparts to the line permutations of positive and negative impulses which are varied in accordance with the operation of the tape-controlling switches C and pole-changers g and which represent the 35 different character signals. As the transmitter switch passes over the contact 6, a negative restoring and printing impulse is imparted to the line, and as it passes over the contacts 7 and 8, a negative correcting 40 impulse followed by a positive impulse is transmitted.

When the feed of the tape is arrested by the operation of the trip pin 73, the transmitter switch e continues its operation to 45 impart the correcting impulses to the line. To prevent this continued operation of the switch e from repeating character signals in accordance with the position of the switches C and pole-changers g, means is provided for 50 interrupting the transmission of such character signals when the feed of the tape is arrested. For this purpose, an insulated cam K is mounted on the shaft 45 and is arranged to coöperate with a switch arm k 55 (see Figs. 1, 4 and 7). Switch k is mounted on a block 90 and is insulated therefrom as shown in Fig. 4. This block is pivoted on an angle bracket 91, which is fixed to the base plate 31 and spring 92 interposed between the block and a clip 93 on the bracket 60 holds the switch in engagement with the cam K. The switch coöperates with an insulated contact screw 94, which is mounted upon a bracket 95 that projects upwardly 65 from the base plate. The switch k is con-

nected to one of the battery wires 24 (see Fig. 7), while its contact 94 is connected by a conductor 96 to the coil of a magnet J which operates the switch j. The coil of this magnet is also connected to the ground 70 or by a suitable return wire to the local battery H.

During the greater part of the revolution of the shafts 45 and 58 and of the transmitter switch arm e, the cam K holds the switch k in open position. When the switch drops into a notch 97 in the cam, it engages the contact 94 and closes the circuit of the magnet J. This notch is so located with respect to the clutch dog 67 that the circuit 80 of the magnet J is thus held closed whenever the clutch dog is tripped to arrest the movement of the shaft 45 and of the tape feeding mechanism, so that the switch j is shifted to disconnect the normally engaged 85 contacts of the pole changers g from the negative termination of the divided battery H', and the transmission permutations of positive and negative impulses or character signals is interrupted. Preferably, the 90 switch j is provided with a normally disengaged contact, which is connected to the conductor 88 by the conductor 98, so that, when the feed of the tape is arrested and the magnet J is energized by the operation of 95 the switch k, all of the contacts of the pole changers g and also the contact 6 of the transmitter disk, are connected to the positive terminal of the battery H', and all the impulses imparted by the transmitter 100 switch e are positive, except the negative correcting impulse which is imparted to the line as the switch passes over the contact 7. In the system to which the invention is applied, the positive impulses have no effect 105 on the receiving instrument at a distant station and, when the feed of the tape is interrupted, no impulses are transmitted to the line which will affect the instrument at the receiving station, except the correcting impulse. The latter, however, is imparted to 110 the line and the instrument at the receiving station is maintained in synchronism with the transmitter and is ready to receive the character signals as soon as the feed of the 115 tape and the transmission of the character signals is resumed.

The transmitter switch arm e is fixed to a hub 99, which is mounted on, but insulated from the shaft 58. The switch arm carries 120 a brush 100 which moves over the contacts of the transmitter disk E, and also is preferably provided with a piece of felt 101 which is saturated with oil and moves over the contacts to remove dust therefrom. The 125 hub 99 is engaged by a brush 102, which is pivotally mounted and spring-pressed into engagement with the hub in the manner already described, in connection with the switch k.

The form of instrument shown in Figs. 1, 2, 3, and 4 is designed for a station such as a news-distributing point, from which messages are transmitted to a number of receiving stations. Such an instrument is preferably provided with means for recording the messages transmitted. For this purpose, a contact disk M is mounted upon the upper annular portion of the bracket 57, and a switch arm m which co-operates with the disk is mounted on the shaft 45. The home recording disk M and switch arm m are similar in construction and arrangement to the transmitting disk and switch arm, the disk M having contacts 1, 2, 3, 4, 5 and 6 corresponding to those of the transmitter disk. But on the home recording disk the contacts 7 and 8 are not required.

The contacts 1, 2, 3, 4 and 5 of the home recording disk M are connected by a set of conductors 103 to the coils of a set of five magnets N. The conductors are also connected to the switches n of these magnets. The contact 6 of the disk M is connected by a conductor 104 to the coil of a magnet P and to a switch p controlled by this magnet. The switches n are normally open and the contacts thereof are connected by a conductor 105 to the contact of a normally closed unlocking switch r. This switch is connected to the battery wire 24 and is operated by a magnet R. The coil of the magnet R is connected by a conductor 104' to the contact of the normally open switch p.

The clutch members 67 and 65 connect the shafts 45 and 58 and the switch arms m and e thereon in definite relation, and, in normal operation, when the clutch members are in engagement, the switch arms rotate in unison and pass over the corresponding contacts 1, 2, 3, 4, 5 and 6 synchronously. The brush 102 of the transmitter switch arm is connected by a conductor 106 to the coils of a polarized relay S, the switch tongue s of which is connected to the local battery wire 24. The contact of this switch tongue is connected by a conductor 107 to the brush 108 of the recording switch arm m. Negative impulses through the relay S will hold the relay switch tongue s in closed position, but positive impulses will shift it to open position. As the switches C are variably operated by the tape, the pole changing magnets G are variably operated and, by means of the pole changers g and the conductors 86, 87 and 88, the contacts 1, 2, 3, 4 and 5 of the transmitter disk E are variably connected either to the positive or the negative pole of the divided battery H', while the contact 6 is connected to the negative pole thereof. As the transmitter switch e passes over these contacts, these positive and negative impulses are transmitted through the relay S and the relay tongue s is vibrated in accordance

therewith to connect the switch arm m to the battery or to disconnect it therefrom.

This switch arm, as stated, operates in unison with the transmitter switch arm, so that as it passes over the contacts 1, 2, 3, 4 and 5, it will variably operate the magnets N in accordance as to whether or not it is connected to the battery as it passes over the corresponding contacts. That is to say, if the switch arm m is connected to battery as it passes over the contact 1, the first one of the set of magnets N will be energized. If the switch arm m is not connected to battery at this time, the first magnet N will not be operated. In this way, the set of magnets N are variably operated as the switch arm m rotates and in accordance with the permutations of positive and negative impulses imparted by the transmitter switch e.

When any one of the magnets N is energized in this way, it operates the corresponding switch n and a circuit can be traced from the battery wire 24, locking switch r, conductor 105, to the shifted switch n, and thence through the coil of the corresponding magnet N. In this way, the magnets N that are operated remain energized until the switch arm m passes over the restoring contact 6. At this time, the transmitter switch arm e passes over its contact 6 and a negative impulse will pass through the relay S to thereby connect the switch arm m to battery and close a circuit through the magnet P. This magnet quickly shifts its switch p so that the circuit is also closed through the magnet R. The latter then opens the unlocking switch r and disconnects all of the operated magnets N from battery and the set of magnets N are then in condition for operation in accordance with the succeeding character signal. The set of magnets N can of course be employed for operating a suitable printer to record the transmitted messages.

The form of instrument shown in Fig. 6 is designed for a station which both transmits and receives messages. For this purpose, the motor 64 is arranged to operate both the transmitter switch mechanism and a receiver switch mechanism. Preferably, the receiver switch mechanism is mounted upon a separate shaft and is geared to the transmitter mechanism to rotate at a slightly faster speed. In this preferred form, the shaft 58', which carries the transmitter switch arm e is extended at its inner end, is journaled in a bracket 109 which extends upwardly from the base plate 31', and is provided with a gear 110. Furthermore, in this instrument the home recording disk and switch arm on the shaft 45 are omitted and the outer end of this shaft is journaled in a bracket 57'. In other respects, the construction of the transmitter and tape feeding mechanism is the same as that shown in Figs. 1 to 5 inclusive, the upper portion of Fig. 6 being substan-

tially a plan view of the parts shown in Figs. 1 to 5 inclusive.

The receiving switch mechanism comprises a disk T, which is mounted upon a bracket 111 on the base plate, and which, like the home recording disk M, heretofore described, is provided with a series of contacts 1, 2, 3, 4, 5 and 6. (See Fig. 7.) The coöperating rotating switch arm t is similar in construction and arrangement to the rotating switch arms e and m and is mounted on a shaft 112 which extends through the disk E and is journaled at its outer end in a U-shaped member 113 on the bracket 111. The disk T is preferably rotatably adjustable, being held in place on the bracket 111 by clips 114. The opposite end of the shaft 112 is journaled in the bracket 109 and carries a sleeve 115 loosely mounted thereon. This sleeve is provided with a gear 116, which is connected to the gear 110 by an intermediate idler 117, that is mounted upon the bracket 109. Sleeve 115 also has a smaller gear 118, which meshes with a pinion 119. The pinion is journaled on a short shaft 120 which is carried by an arm 121 that is keyed to the shaft 112. The opposite end of the short shaft 120 is provided with a star wheel 122, the teeth of which are engaged by a roller 123 on a spring-held arm 124. The arm 124 is mounted on the arm 121 and normally prevents the rotation of the star wheel 122 and the relative rotation of the gears 118 and 119, so that the shaft 112 and receiver switch arm t rotate in unison with the gear 116. A correcting magnet V is provided with an armature lever 126 having a pin 127 thereon (see Figs. 6 and 7). When this magnet is energized, the pin 127 is projected into the teeth of the star wheel 122 and the movement of the shaft 112, and receiver switch arm t thereon, is retarded. The circuit of this magnet is controlled by the line relay at the receiving station (which of course is controlled by the transmitter at the sending station) and by a switch w at the receiving station. The switch w is operated by a cam W on the shaft 112, the construction of these parts being similar to cam K and switch k previously described. That is to say, the cam serves to normally hold the switch in open position, but when a notch 128 is in line with the switch, the latter engages a contact 129.

Fig. 7 shows the transmitting and home recording circuits at one station and the receiving circuits at another station. The brush 102 which engages the transmitter switch *e* is, as above stated, connected to the relay *S* that controls the home recorder, if one is employed. The brush 102 may also be connected, if desired, directly to the line circuit, but it preferably extends through the coils of a polarized transmitting relay

X, having a switch tongue x . The contacts of the switch tongue are connected by conductors 130 to the positive and negative poles of a divided line battery H".

If the station is used for transmitting only, the tongue x of the transmitter relay is connected directly to the line conductor. If means are provided at each station both for transmitting and receiving, the line is arranged for duplex operation and the tongue x of the transmitting relay is connected by a conductor 131 and a pair of branch conductors 132 to the coils of a polarized line relay Y. These coils are also respectively connected to the line conductor 133 and to a balancing artificial line 134. The switch tongue y of the line relay Y at each station, is connected by one of the branch conductors 24 to the local battery H and the contact of this switch tongue is connected by a conductor 135 to the brush 136 of the receiving switch arm t. The conductor 135 is also connected to the switch w and the contact 129 of the latter is connected by a conductor 137 to the correcting magnet V. The circuits controlled by the receiving switch mechanism are similar in all respects to that controlled by the home recording switch mechanism.

It will be understood that where the connected stations both transmit and receive messages, both stations will be equipped with tape-forming means, transmitting and receiving mechanism and the necessary transmitting and receiving circuits. In such cases, as stated, the line is arranged for duplex operating, the line relay at each station responding only to messages transmitted from the other station, so that messages can be simultaneously transmitted and received at the connected stations without interference. When messages are transmitted in one direction only, the line relay and the connected receiving apparatus and circuits are omitted at the transmitting station, and the transmitting relay and connecting transmitting apparatus and circuits are omitted at the receiving station or stations. Whether the line is arranged for transmission of messages in both directions or in one direction only, the rotating receiver switch at a station is driven slightly faster than the transmitter at the distant station and the receiver switch is retarded as required by the correcting devices. The gearing of the combined transmitting and receiving instruments shown in Fig. 6 is such that the receiving switch t is driven slightly faster than the transmitting switch of the same instrument and also slightly faster than the transmitting switch at the distant station.

Briefly stated, the operation of transmitting messages in one direction is as follows. The tape is formed under control of the finger-keys 20 and of the punch-actuating mag- 130

net B, and is advanced by the intermittently operating feed wheel 27 of the tape former. Thence the tape passes around the pin 81 of the switch F and through the guide-way between the plates 32 and 33 of the transmitter. Here it is engaged by the feed wheel 30 and moves past the switches C. When the shafts 45 and 58 are connected by the clutch members, the feed wheel 30 is continuously 10 rotated in definite timed relation with the rotating transmitter switch *e*, the gearing being such that as the switch rotates through a single revolution, the tape is advanced a space equal to the distance between the transverse rows of perforations *a*. The set of switches C are preferably arranged at right angles to the path of movement of the tape and the transverse rows of perforations *a* are slightly inclined thereto, as shown in 15 Fig. 8, so that the tape may be continuously advanced and at the same time permit the accurate register of the switches C with the perforations of the tape as the transmitter switch *e* passes over the corresponding contacts 1, 2, 3, 4 and 5.

As the tape passes beneath the switches C, the magnets G are variably energized and the pole changers *g* variably actuated to connect the contacts 1, 2, 3, 4 and 5 of the transmitter disk either to the positive or negative terminal of the divided battery H', and as the transmitter switch passes over these contacts and over the contacts 6, 7 and 8, permutations of impulses of opposite polarity 30 representing the characters will be transmitted, each character signal being followed by negative restoring and correcting impulses and a positive impulse. These impulses are imparted to the line by the transmitting relay X at the sending station, and the line relay Y at the distant receiving station will be operated in accordance therewith to shift the switch tongue *y* and open and close the local circuit through the conductor 135. If a home recorder is employed 40 at the sending station, the transmitted impulses will pass through the relay S and open and close the local circuit through the home recording switch *m*. The operation of this 45 switch will, as described, variably operate a set of magnets N and the latter in turn will actuate a suitable printing mechanism. At the receiving station, the line relay switch Y and the rotating receiving switch *t* will 50 operate in a similar manner to actuate a set of printer controlling magnets N at that station.

The correcting magnet V at the receiving station is connected to local battery 60 through the medium of the switch *w* and the line relay switch *y*, both of which must be simultaneously closed for a sufficient interval of time to energize the correcting magnet. As the character signals and the restoring 65 impulse are received, the cam W will hold

the switch *w* open. As the transmitter switch *e* of the sending station passes over the contact 7 and imparts a correcting impulse to the line, the switch *y* of the line relay Y at the receiving station will be closed. 70 This negative impulse is quickly followed by a positive impulse as the transmitting switch passes over its contact 8, so that the line relay switch *y* is only closed for a brief interval. During this brief interval, the 75 switch *w* will not be closed, or will not be closed for a sufficient length of time to energize the correcting magnet V. But as the receiver switch mechanism gains over the transmitting switch mechanism at the sending station, both the line relay switch *y* and the switch *w* at the receiving station will be simultaneously closed for a sufficient time to energize correcting magnet V, and the movement of the receiving switch *t* will be retarded. 80

At the sending station, the contact 76 of the tape actuating switch F is connected to the local battery and the contact 77 is connected by a conductor 138 to the coil of the clutch controlling magnet D. Normally, these contacts are in engagement and the magnet is energized to hold the trip pin 73 in its inoperative position. If the operation of the tape former is interrupted, the tension of the tape will shift the switch F, open the circuit of the magnet D and the trip pin will be projected into the path of the clutch members. The latter, after the character signal then being transmitted to the line is 95 completed, will be disengaged and the operation of the transmitting tape feeder and also of the home recorder, if one is employed, will be arrested. At the same time, the cam K on the shaft 45 will be arrested 100 with the notch 97 therein opposite the switch *k* so that the latter will engage its contact 94 and close a circuit from battery wire 24 through contact 94 and conductor 96 to the magnet J. Switch *j* is then shifted 105 into engagement with its front contact and all of the contacts of the pole changers *g* will be connected to the positive terminal of the battery H'. Then positive impulses only 110 will be imparted to the line, except that once every revolution as the transmitter switch *e* passes over the contact 7 it will transmit a negative correcting impulse. Thus the switch *y* of the line relay at the receiving station will be held open, except that it will 115 be closed at intervals by the negative correcting impulses. These correcting impulses will maintain the receiving switch mechanism at the distant station in synchronism with the transmitter switch mechanism at 120 the sending station and ready to receive character signals as soon as the feed of the tape at the sending station is resumed. This of course occurs as soon as the operation of the tape former relieves the tension of the 125 tape. 130

tape and permits the closing of the switch 5 F to thereby energize the magnet D and withdraw the trip pin 73. Then, after the transmitter switch has passed over its contact 6, the clutch member will again connect the shafts 45 and 58 to continue the transmission of the character signals.

The improvement insures the transmission of the messages as fast as the tape is 10 formed and avoids the necessity of first forming the tape and subsequently and separately running it through the transmitter mechanism.

It is obvious that numerous changes may 15 be made in the details set forth without departure from the essentials of the invention as defined in the claims.

We claim as our invention:

1. In telegraphs, the combination with 20 a rotary transmitter switch and a tape feeder, of mechanical driving connections between said switch and feeder for operating the same in definite timed relation, a trip for stopping and starting said feeder 25 while permitting the continued operation of said switch, a tape former and a tape actuated device between said former and said tape feeder for controlling said trip.

2. In telegraphs, the combination with a 30 rotary transmitter switch mechanism, and a tape feed-wheel, of a common drive shaft mechanically connected to said switch mechanism and said feed-wheel for rotating the same in timed relation, a former for the 35 tape having a means for advancing the tape, means for operating said tape-former independently of said transmitter switch mechanism, and means controlled by the movement of the tape between said former 40 and said feed-wheel for automatically stopping and starting the latter.

3. In telegraphs, the combination with a 45 rotary transmitter switch mechanism, a set of tape controlled switches for selecting the transmitted impulses, a tape feed-wheel, and means for constantly rotating said switch mechanism and said tape feed-wheel in timed relation, of a former for the tape having a tape feed-wheel, means for actuating said tape-former and its feed-wheel independently of said transmitter switch mechanism, a tape-actuated switch interposed between said feed-wheels, and means controlled thereby for throwing said transmitter feed-wheel into and out of operation.

4. In telegraphs, the combination with a 50 rotary transmitter switch mechanism, a set of tape-controlled switches for selecting the transmitted impulses, a tape feed-wheel, and means acting, when in operation, to actuate said switch mechanism and said feed-wheel in definite timed relation therewith, of a punch for forming the tape having a tape feed-wheel, means for intermit-

tently actuating said punch and its feed-wheel, and means including two rotary clutch members and a disengaging trip therefor controlled by the movement of the tape between said feed-wheels for stopping 70 and starting said transmitter feed-wheel.

5. In selective telegraphs, the combination with a transmitter switch and a tape feeder, of mechanical driving connections between said switch and feeder for operating the same in definite timed relation, a trip mechanism arranged to act only between completed signals for stopping and starting said feeder while permitting the continued operation of said switch, a tape 80 former operable independently of said tape feeder and means under the joint control of said tape former and said feeder for controlling said trip mechanism.

6. In selective telegraphs, the combination with transmitter switch mechanism, a tape feeder and operating means therefor, of a clutch for mechanically connecting said switch mechanism and said tape feeder in definite relation, said clutch being operable 90 to stop and start said feeder while permitting the continued operation of said switch mechanism, a trip arranged to control said clutch only between completed signals, a tape former, means for operating the latter 95 independently of said switch mechanism and said feeder and means controlled by the operation of said tape former for actuating said trip.

7. In selective telegraphs in which the 100 signals are represented by combinations of impulses, the combination with transmitter switch mechanism, of a set of tape-controlled switches for selecting the transmitted impulses, a tape-feeder for constantly advancing the tape past said switches in timed relation to the operation of said transmitter switch mechanism, a former for the tape, means for operating the same independently of said transmitter switch mechanism, a 110 tape-actuated switch interposed between said former and said tape feeder, and means controlled thereby and arranged to act only between completed signals for interrupting the operation of said tape-feeder and of said 115 impulse-selecting switches.

8. In synchronous selective telegraphs in which the signals are represented by combinations of impulses, the combination with a set of tape-controlled switches for selecting the impulses, switch mechanism for transmitting the selected impulses and a correcting impulse, a tape feed-wheel, and means for operating said transmitter switch mechanism and for constantly rotating said 125 feed wheel in timed relation with said transmitter switch mechanism, of means arranged to act only between completed signals to interrupt the operation of said impulse selecting switches and said tape-feeder, a 130

former for the tape and means controlled by the operation of said former for controlling said interrupting means.

9. In synchronous selective telegraphs in which the signals are represented by combinations of impulses, the combination with tape controlled devices for selecting the impulses, switch mechanism for transmitting the selected impulses and a correcting impulse, a tape-feeder, and means for operating said transmitter switch mechanism and said feeder in timed relation, of means for interrupting the operation of said impulse selecting devices, a clutch for mechanically connecting said interrupting means and said tape-feeder to said switch mechanism in definite relation thereto, a trip arranged to disengage said clutch only between completed signals, a former for the tape operative independently of said transmitter switch mechanism, and means controlled by the operation of said former for actuating said trip.

10. In synchronous selective telegraphs in which the signals are represented by combinations of impulses, the combination with a rotary switch mechanism for transmitting the signals and correcting impulses, of a tape-feeder, a clutch mechanically connecting said switch mechanism and said tape-feeder in definite relation, a trip for disengaging said clutch between completed signals, a tape former and means controlled by the operation of said former for actuating said trip.

11. In synchronous selective telegraphs in which the signals are represented by combinations of impulses, the combination with a rotary switch mechanism for transmitting the signals and correcting impulses, of a tape-feeder, a clutch mechanically connecting said switch mechanism and said tape-feeder in definite relation, a trip for disengaging said clutch between completed signals, a punch for forming the tape having a tape-feeder, means for actuating said punch independently of said transmitter switch mechanism, a tape-actuated switch controlled by the operation of the tape-feeder of said punch, and means controlled by said switch for actuating said trip.

12. In synchronous selective telegraphs in which the signals are represented by combinations of impulses, the combination with a set of tape-controlled switches for selecting the signals, a rotary switch mechanism for transmitting the signals and correcting impulses, and a tape feed-wheel, of a rotary cam, means controlled thereby for interrupting the operation of said selecting switches, clutch mechanism for connecting said cam and said feed-wheel to said transmitter switch in definite relation, trip devices for said clutch mechanism, a former for the tape operative independently of

said transmitter switch mechanism and having means for advancing the tape and means controlled by the movement of the tape between said former and said feed-wheel for actuating said trip.

13. In synchronous selective telegraphs in which the signals are represented by combinations of impulses, the combination with a set of tape-controlled switches for selecting the signals, a rotary switch mechanism for transmitting the signals and correcting impulses, a tape feed-wheel, and means for continuously rotating said switch mechanism and said feed-wheel, of a clutch for connecting said switch mechanism and feed-wheel in definite relation, a trip for releasing said clutch between completed signals, a punch for forming the tape having a tape feed-wheel, means for intermittently operating said punch and its feed-wheel, and means controlled by the operation of said punch for actuating said trip.

14. In synchronous selective telegraphs in which the signals are represented by permutations of a definite number of impulses of opposite polarity, the combination with a set of tape-controlled pole-changers for selecting signals, continuously operating switch mechanism for transmitting the signals and correcting impulses, a tape feed-wheel, and means for constantly operating said feed-wheel in timed relation with said transmitter switch mechanism, of means arranged to operate between completed signals for interrupting the operation of said pole-changers and of said feed-wheel, a former for the tape operative independently of said transmitter switch mechanism and having means for advancing the tape, and means controlled by the movement of the tape between said former and said tape-feeder for controlling said interrupting means.

15. In synchronous selective telegraphs in which the signals are represented by permutations of a definite number of impulses of opposite polarity, the combination with a set of tape-controlled pole-changers for selecting signals, continuously operating switch mechanism for transmitting the signals and correcting impulses, a tape-feeder, and means for operating said feeder in timed relation with said transmitter switch mechanism, of interrupting devices arranged to operate between completed signals to connect all the contacts of said pole-changers to the same battery terminal and to throw said tape-feeder into and out of operation, a former for the tape operative independently of said transmitter switch mechanism, and a tape-actuated switch interposed between said former and said tape-feeder for controlling said interrupting devices.

16. In synchronous selective telegraphs in which the signals are represented by permu-

tations of a definite number of impulses of opposite polarity, the combination with a continuously rotating switch mechanism for transmitting the signals and correcting 5 impulses, a set of tape-controlled pole-changers for selecting the signals, and a tape feed-wheel, of a rotary member, means controlled thereby for intermittently connecting the contacts of said pole-changers to the same 10 battery terminal, a clutch for connecting said rotary member and said feed-wheel to said rotary switch mechanism in definite relation, a trip for releasing said clutch between completed signals, an intermittently 15 operating punch for forming the tape having tape advancing means, and devices controlled by the operation of said tape-advancing means for actuating said trip.

17. In a selective telegraph in which the 20 signals are represented by combinations of impulses, the combination with switch mechanism for transmitting the signals, tape-controlled switches for selecting the combinations of impulses, and means for 25 constantly feeding the tape past said switches in timed relation with the operation of said transmitter switch mechanism, of means acting only between completed signals for interrupting the transmission of the 30 selected impulses and the feed of said tape, a former for the tape operative independently of said transmitter switch mechanism, and means controlled by the operation of said tape former for actuating said interrupting means.

18. In a synchronous selective telegraph 35 in which the signals are represented by combinations of impulses, the combination with tape-controlled devices for selecting the signals, continuously operating switch mechanism for transmitting the signals and restoring 40 and correcting impulses, a tape-feeder and means for operating said feeder in timed relation with said transmitter switch mechanism, of means arranged to act only between completed signals for interrupting the 45 operation of said tape-feeder and the transmission of selected impulses and of the restoring impulses while permitting the continued transmission of the correcting impulses, a former for the tape operative independently of said transmitter switch mechanism and means controlled by the operation of said tape former for actuating said interrupting means.

19. In a synchronous selective telegraph 50 in which the signals are represented by permutations of a definite number of impulses of opposite polarity, the combination with tape-controlled pole-changers for selecting the signals, a rotary switch mechanism for transmitting the selecting impulses and restoring and correcting impulses, of a tape-feeder, a 55 rotary member, means controlled by said member for changing the polarity of the re-

storing impulse and for connecting all the contacts of said pole-changers to the same battery terminal, a clutch for connecting said tape-feeder and said rotary member to said rotary switch mechanism in definite 70 relation thereto, a trip for said clutch, a tape former operative independently of said switch mechanism, a tape actuated switch controlled by the operation of said tape former and means controlled by said switch for 75 actuating said trip.

20. In selective telegraphs in which the signals are represented by combinations of impulses, the combination with tape-controlled means for selecting the signals, and a 80 switch mechanism for transmitting the selected signals, of a home recording switch mechanism, a tape-feeder, means for operating said switch mechanisms and said tape-feeder in timed relation, an independently 85 operative tape-former, and means controlled by the operation of said former and acting only between completed signals for interrupting the operation of said home recording switch mechanism and said tape-feeder. 90

21. In selective telegraph instruments, the combination of a rotary transmitter switch, tape controlled means for selecting the transmitted impulses, a feeder for engaging and positively advancing the tape, a common 95 drive shaft mechanically connected to said switch and said feeder operating the same in definite timed relation, and a clutch interposed in the mechanical connections between said shaft and said feed wheel and controlled by the movement of the tape for automatically stopping and starting said feed wheel.

22. In selective telegraphs in which the signals are represented by combinations of 105 impulses, the combination of transmitter switch mechanism, a set of tape-controlled switches for selecting the signals, a toothed feed-wheel arranged to constantly engage the tape to positively advance the same, 110 means acting, when in operation, to continuously rotate said feed-wheel, a switch actuated by the movement of the tape, and means controlled thereby for stopping and starting said feed-wheel. 115

23. In a selective telegraph in which the signals are represented by combinations of impulses, the combination of a transmitter having a set of tape controlled signal selecting switches and a tape feeder, an independently operable tape former and means for arresting the operation of said transmitter comprising co-operating rotary clutch members, a trip operable to disengage said clutch members only between completed signals, 120 and means under the joint control of said transmitter and said tape former for actuating said trip. 125

24. In a selective telegraph instrument the combination of a rotating transmitter 130

switch, a set of tape-controlled signal selecting switches, a feed-wheel for advancing the tape, a drive shaft for said transmitter switch, reducing gearing interposed between 5 said shaft and said feed wheel, arranged, when in operation, to continuously rotate said wheel, a clutch for connecting said shaft and gearing, a tape-actuated device, and means controlled thereby and operative 10 only between completed signals for throwing said clutch into and out of operation.

25. In a telegraph apparatus, the combination of tape controlled means for selecting the signals, switch mechanism for 15 transmitting the selected signals, means for feeding the tape in timed relation with said switch mechanism, and means for interrupting the feed of the tape and the transmission of signals comprising co-operating rotary clutch members and a disengaging trip therefor, said rotary clutch members and co-operating trip being operable only between 20 completed signals to start and stop said tape feeding means.

25. 26. In a telegraph apparatus, the combination of tape controlled means for selecting the signals, switch mechanism for transmitting the selected signals, means for feeding the tape in timed relation with said 30 switch mechanism and means for interrupting the feed of the tape and the transmission of signals comprising co-operating rotary clutch members, disengaging trips for said rotary clutch members, said clutch members and said trip being operable only between 35 completed signals to start and stop said tape feeding means, an electromagnet for operating said trip, a tape former and means under the joint control of said tape former and said tape feeding means for controlling 40 the circuit of said magnet.

27. In an instrument for selective synchronous telegraphs, the combination of a set of signal selecting switches, a continuously rotating switch for transmitting the 45 selected signals and correcting impulses, a rotating feed-wheel for the tape, clutch members for connecting said transmitter switch and said feed-wheel to continuously 50 rotate the latter in timed relation with said transmitter switch, a trip for said clutch members operative only between completed signals, and a device actuated by the movement of the tape controlling said trip.

55. 28. In an instrument for selective synchronous telegraphs, the combination of a set of signal selecting switches, a continuously rotating switch for transmitting the selected signals and correcting impulses, a 60 rotating feed-wheel for the tape, clutch members for connecting said transmitter switch and said feed-wheel to continuously rotate the latter in timed relation with said transmitter switch, a trip for said clutch members operative only between com-

pleted signals, a magnet for effecting the movement of said trip to its operative and inoperative positions, and a switch actuated by movement of the tape for controlling said magnet.

29. In a selective telegraph instrument, the combination of a rotary transmitter switch, a set of tape-controlled switches for selecting the signals, a feed wheel for the 75 tape, a rotary member for interrupting the operation of said switches, a clutch for throwing said rotary member and said feed-wheel into and out of operation, and a trip for said clutch operative only between completed signals.

30. In a selective telegraph instrument, the combination of a rotary transmitter switch, a set of tape-controlled pole-changers for selecting the signals, a rotary member, means controlled thereby for connecting the contacts of said pole-changers to the same battery terminal, a tape feed-wheel, clutch members for connecting said feed-wheel and said rotary member to said transmitter switch in definite relation, a trip controlling the engagement and disengagement of said clutch members, a switch actuated by the movement of the tape, and means controlled thereby for actuating said trip.

31. In a selective telegraph instrument, the combination of a rotary transmitter switch, a set of tape-controlled signal selecting switches, a feed-wheel for the tape, drive shafts for said transmitter switch and 100 said feed-wheel arranged in line, speed reducing gearing between said feed-wheel and its drive shaft, a cam on said feed-wheel drive shaft, means controlled thereby for interrupting the operation of said selecting 105 switches, clutch members operative only to connect said shafts in definite relation, a trip operative only between completed signals for disengaging said clutch members, and a tape-controlled means for operating said trip.

32. In a selective telegraph instrument, the combination of rotary transmitting and home recording switch mechanisms, tape-controlled means for selecting the signals, 115 a feed-wheel for positively advancing the tape, and common drive mechanism for continuously rotating said transmitting and home-recording switch mechanisms and said feed-wheel in definite timed relation.

33. In a selective telegraph instrument, the combination of rotary transmitting and home recording switch mechanisms, a set of signal selecting switches, a tape for controlling said switches having transverse rows of perforations representing the signals and also having a longitudinal row of perforations, a pin-toothed feed-wheel arranged to engage the longitudinal row of perforations of said tape to move the same 130

past said selecting switches, said transverse rows of perforations and said set of selecting switches being relatively inclined, and common drive mechanism for rotating said transmitting and home recording switch mechanisms and said feed-wheel in timed relation.

34. In a selective telegraph instrument, the combination of rotary transmitting and home recording switch mechanisms, tape-controlled means for selecting the signals, a feed-wheel for positively advancing the tape, clutch members for connecting said feed-wheel and said home recording switch mechanism to said transmitter switch, means for continuously rotating said transmitter switch, a trip operative only between completed signals for controlling the engagement and disengagement of said clutch members, and tape-controlled means for shifting said trip.

35. In an instrument for synchronous selective telegraphs, the combination of rotary transmitting and receiving switch mechanisms, a common drive shaft therefor, tape-controlled means for selecting the transmitted impulses, a feed-wheel for advancing the tape, clutch members for connecting said feed-wheel and said transmitter switch mechanism in definite relation, a trip operative only between completed signals to disengage said clutch members, tape-actuated means for controlling said trip, and correcting devices for shifting said receiving switch mechanism relatively to said drive shaft.

36. In an instrument for synchronous selective telegraphs, the combination of rotary transmitting and receiving switches, a drive shaft whereon said transmitter switch is mounted, connecting gearing between said shaft and said receiver switch, correcting devices for shifting said receiver switch relatively to said gearing, tape-controlled signal selecting switches, a feed-wheel for the tape, clutch member between said drive shaft and said feed wheel for connecting the latter to said transmitter switch in definite relation, a trip operative only between completed signals for disengaging said clutch member, and tape-actuated means for controlling said clutch.

37. In a synchronous telegraph in which the signals are represented by combinations of impulses, the combination of a rotating transmitter switch at one station for imparting the signals and correcting impulses to the line, a receiving switch mechanism at a connected station having means acting in response to the correcting impulses to maintain the same in synchronism with said transmitter switch, tape-controlled signal selecting means at the transmitting station, a feed-wheel for the tape, clutch members for mechanically connecting said feed-

wheel and said transmitter switch, and means for disengaging said clutch members and for interrupting the transmission of signals without interrupting the transmission of the correcting impulses. 70

38. In a synchronous telegraph in which the signals are represented by combinations of impulses, the combination of a rotating transmitter switch at one station for imparting the signals and correcting impulses 75 to the line, a receiving switch mechanism at a connected station having means acting in response to the correcting impulses to maintain the same in synchronism with said transmitter switch, tape-controlled signal selecting means at the transmitting station, a feed-wheel for the tape, clutch members for mechanically connecting said transmitter switch and feed-wheel in definite relation, a trip operative only between complete signals 80 for disengaging said clutch members, a tape-former at the transmitting station operative independently of said transmitter switch, and means controlled by said tape-former for shifting said trip. 90

39. In synchronous selective telegraphs in which the signals are represented by permutations of a definite number of impulses of opposite polarity, the combination of a continuously rotating transmitter switch at 95 one station for imparting the signals and correcting impulses to the line, a continuously rotating receiver switch at a connected station having means acting in response to the correcting impulses for maintaining the 100 same in synchronism with said transmitter switch, a set of tape controlled pole-changers at the transmitting station, a feed-wheel for the tape, a rotary member for intermittently connecting the contacts of said 105 pole-changers to the same battery terminal, clutch members for connecting said rotary member and said feed-wheel to said transmitter switch in definite timed relation, and a device actuated by the movement of the 110 tape for controlling the engagement and disengagement of said clutch members.

40. In synchronous selective telegraphs in which the signals are represented by permutations of a definite number of impulses 115 of opposite polarity, the combination of a continuously rotating transmitter switch at one station for imparting the signals and correcting impulses to the line, a rotating receiver switch at a connected station having means acting in response to the correcting impulses for maintaining the same in synchronism with said transmitter switch, a set of tape-controlled pole-changers at the transmitting station, a feeder for the tape, 120 a tape-former operative independently of said transmitter switch, means controlled by the operation of said tape-former for interrupting the feed of the tape, and devices controlled by said interrupting means for 130

connecting all the contacts of said pole-changers to the same battery terminal.

41. In a synchronous selective telegraph, the combination with a line circuit, of rotary transmitting and receiving switch mechanism at each of two connected stations, and means at all times under the control of the transmitter switch mechanism at each station and the receiver switch mechanism at the other station for maintaining the same in synchronism, each station having a set of tape-controlled selecting switches, a tape feeder, means for operating said feed-wheel and said rotary transmitter switch mechanism in definite relation, and tape-controlled trip devices operative only between completed signals for automatically stopping and starting said feeder.

42. In synchronous selective telegraphs in which the signals are represented by permutations of a definite number of impulses of opposite polarity, the combination with a duplexed line circuit, of rotary transmitting and receiving switch mechanisms at each station, and means at all times under the control of said switch mechanism for maintaining the same in synchronism, each station having a set of tape-controlled pole-changers for selecting the signals, a tape feed-wheel for advancing the tape in timed relation with said transmitter switch mechanism, tape-controlled means for interrupting the feed of the tape, and devices controlled by said interrupting means for connecting all the contacts of said pole-changers to the same battery terminal.

43. In selective telegraphs in which the signals are represented by combinations of impulses, the combination of transmitter switch mechanism for imparting the signals to the line, a tape-former operative independently of said switch mechanism, means for advancing the tape in timed relation with the operation of said transmitter switch mechanism, a set of impulse selecting switches projecting into the path of the tape and arranged to be engaged and operated solely thereby, and devices controlled by the operation of said tape-former for automatically stopping and starting the feed of the tape and the transmission of signals.

44. In selective telegraphs in which the signals are represented by combinations of impulses, the combination of transmitter switch mechanism for imparting the signals to the line, a tape-former operative independently of said switch mechanism, means for advancing the tape in timed relation with the operation of said transmitter switch mechanism, a set of impulse selecting switches projecting into the path of the tape and arranged to be engaged and operated solely thereby, a tape actuated switch controlled by the operation of said tape-former, and devices under control of said

switch and operative only between completed signals for automatically stopping and starting the feed of the tape and the transmission of signals.

45. In selective telegraphs in which the signals are represented by combinations of impulses, the combination of a transmitter switch, an independently operative tape punch, a tape guide-way, a feed wheel for the tape, means acting when in operation to constantly rotate said feed wheel in timed relation with the operation of said rotary transmitter switch, a set of impulse selecting switches projecting into said tape guide-way and arranged to be engaged and operated solely by the tape, a device automatically controlled by the operation of said tape-former for stopping and starting said feed-wheel and the transmission of signals, said start and stop devices being arranged to operate only between completed signals.

46. In synchronous selective telegraphs in which the signals are represented by combinations of impulses, the combination of switch mechanism for transmitting the signals and correcting impulses, an independently operative tape former, means for advancing the tape in timed relation with the operation of said transmitter switch mechanism, a set of signal selecting switches arranged to be engaged and operated solely by the tape, and devices automatically controlled by the operation of said tape-former for stopping and starting the feed of the tape and the transmission of signals without interrupting the transmission of the correcting impulses, said stop and start devices being arranged to operate only between completed signals.

47. In synchronous selective telegraphs in which the signals are represented by combinations of impulses, the combination of switch mechanism for transmitting the signals and correcting impulses, an independently operative tape-former, a feed-wheel for the tape, means acting, when in operation to constantly advance the tape in timed relation with said transmitter switch mechanism, a set of signal selecting switches arranged to engage and be operated by the tape, a tape-actuated switch automatically controlled by the operation of said tape-former, and devices controlled by said switch and operative only between completed signals for stopping and starting said feed-wheel and the transmission of signals without interrupting the transmission of the correcting impulses.

48. In synchronous selective telegraphs in which the signals are represented by combinations of impulses of opposite polarity, the combination of a closed line circuit, switch mechanism for transmitting the signals and correcting impulses over said line circuit, a tape-former, means for advancing the tape

in timed relation with the operation of said transmitter switch mechanism, a set of impulse selecting switches arranged to be engaged and operated solely by the tape, and devices automatically controlled by the operation of said tape-former for stopping and starting the feed of the tape and the transmission of signals without interrupting the flow of current in said line circuit 5 and the transmission of correcting impulses, said stop and start devices being arranged to operate only between completed signals.

49. In a selective telegraph in which the signals are represented by combinations of impulses, the combination with a set of tape controlled switches for selecting the signals, a rotary switch and a tape feed wheel, of a rotary member, means controlled thereby for interrupting the operation of 10 said selecting switches, and start and stop mechanism for said rotary member and said tape feed wheel comprising coöperating rotary clutch members, a disengaging trip therefor operable only between completed 15 signals, a tape former, and means under the joint control of said tape former and said tape feed wheel for controlling the operation of said trip.

50. In selective telegraphs in which the signals are represented by combinations of impulses, the combination of a rotary transmitter switch member, a set of tape-controlled impulse selectors, a toothed feed

wheel arranged to engage and positively advance the tape, a common drive shaft, and 35 mechanical connections acting, when in operation, to constantly rotate said transmitter member and said feed wheel in timed relation to impart successive signals to the line, a tape former, and means operative 40 only between completed signals for interrupting the feed of the tape and the transmission of signals and comprising a rotary clutch interposed in said mechanical connections and a coöperating trip therefor 45 controlled by the operation of said tape former.

51. In a selective telegraph in which the signals are of uniform length and represented by permutations of impulses, the 50 combination of a set of tape-controlled impulse selectors, a rotary transmitter switch member coöperating therewith to impart the signals to the line, means for feeding the tape in timed relation with the operation of 55 said rotary switch member, a tape former, and means operative only between complete signals for stopping and starting the feed of the tape and the transmission of signals and comprising a rotary clutch, a coöperat- 60 ing trip therefor and means controlled by the operation of said tape former for actuating said trip.
